(57) **CLAIM**

The ornamental design for a stylus pen as shown and described.

DESCRIPTION

FIG. 1 is a perspective view of a stylus pen showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an embodiment in which the top of the stylus pen is in sliding up status thereof.

The broken lines depict portions of the stylus pen that form no part of the claimed design.
